GOLF TEE FOR CORRECTING
A HOOK OR SLICE

Charles W. Post, Eastview Drive, V3, Maywood Park,
P.O. Box 182, Chesterland, Ohio 44026
Filed Jan. 2, 1964, Ser. No. 335,007
9 Claims. (Cl. 273—207)

This invention is directed to an improved golf tee and more particularly relates to a golf tee which enables golfers to control the direction of flight of a golf ball hit from such tee.

The major problem with which the vast majority of golfers is confronted is that of controlling the direction of flight of the golf ball. The common experience of most golfers is to have the golf ball execute either what is referred to as a "hook" or a "slice," i.e., a sharp curving of the ball in flight to the left or right respectively, depending upon the particular deficiencies in the swing of each individual golfer. Prior to this invention, there has been no satisfactory solution to this problem, other than improved proficiency resulting from continued and extensive practice.

It is an object of this invention therefore to provide a novel golf tee which is relatively simple in construction and which will enable the ordinary golfer to achieve continually straight drives.

It is another object of this invention to provide a golf tee which will enable a golfer to control the direction of flight of the golf ball by rotatably indexing the position of the golf tee and golf ball relative to the face of the golf club contacting same.

Yet another object is to provide a device for controlling the direction of the golf ball and simultaneously enabling a golfer to achieve greater distance from his drives.

Other objects, advantages, and features of this invention will become apparent to those skilled in the art in view of the following more detailed description of the invention.

These and other objects are achieved by means of this invention in which an improved golf tee is provided which comprises a base portion and a pair of vertically extending flexible fingers attached thereto. Each of the fingers is positioned on the base portion so that it is generally diametrically opposite the other finger and spaced therefrom a sufficient distance to support a golf ball near its midportion when placed between the fingers.

To the accomplishment of the foregoing and related ends, the invention, then, comprises the features herein-after fully described and particularly pointed out in the claims, the following description and the annexed drawings setting forth in detail a certain illustrative embodiment of the invention, this being indicative, however, of but one of the various ways in which the principle of the invention may be employed.

In said annexed drawings:

FIG. 1 is a side elevational view of the golf tee with a golf ball properly positioned thereon;

FIG. 2 is a top view of the tee;

FIGS. 3 and 4 are views from the rear and front sides 60 of the tee respectively; and

FIGS. 5-7 schematically illustrate the positioning of the golf tee and golf ball thereon relative to the face of a golf club when employing the device of this invention.

Referring now more in detail to FIGS. 1 to 4 inclusive, the golf tee of this invention is indicated generally by the letter T. A base portion 1 is shown with a pair of flexible vertically extending fingers 2 and 3 attached thereto, either as an integral part of the base portion as illustrated, this being the preferred embodiment, or connected thereto by conventional fastening means such as snap means, a tab and slot engagement, etc. Base portion 1 has a front

2

wall 4 and an undercut 5 in the rear side thereof. Undercut 5 is designed such that it will partially receive the face of a golf club when the club contacts ball B positioned on the tee T and thereby permit the ball to receive the entire initial impact of the club and to be freely removed therefrom. Front wall 4 is of such height that it is below the lower surface of a golf ball when the latter is placed on the golf tee. Accordingly, the front wall will not come in contact with the golf ball and thereby impede its takeoff from the tee but will somewhat rigidify flexible fingers 2 and 3 to insure adequate support for the ball. Tapered portions 6 and 7 of flexible fingers 2 and 3, respectively, are designed to receive the impact from a golf club when striking the ball and tee and to yield under pressure of the club.

The golf tee also has a pair of lip members or ledges 8 and 9 located on the inside of flexible fingers 2 and 3 which assist in supporting and positioning a golf ball placed between the flexible fingers, as illustrated in FIG.

20 1. Lip members 8 and 9 are so located on flexible fingers 2 and 3, and fingers 2 and 3 are spaced apart a sufficient distance that a golf ball will be resiliently gripped approximately at the midpoint (equator) thereof by the upper end portions of such fingers. As illustrated, the flexible fingers are thus the sole means for supporting or gripping the golf ball substantially about its horizontal midportion or equator, with the aforementioned ledges or lips supporting and vertically positioning the underside thereof. The top surfaces or tips of fingers 2 and 3 are 25 also sloped slightly upwardly from the back to the front side of the tee, as indicated at 10 and 11. By sloping the tips of the fingers in this manner, they will be in a position approximately level with the ground at the moment when the golf ball is driven therefrom by impact of the 30 golf club, since the club will ordinarily tip the tee slightly 35 forwardly when making contact with the ball.

The golf tee illustrated will be used as follows. Referring to FIGS. 5 to 7 inclusive, a golf ball B will be positioned on the tee between flexible fingers 2 and 3. The 40 device can be rotatively indexed about its vertical axis either clockwise or counterclockwise and by adjusting the position of the tee and golf ball relative to the direction of contact between the golf ball and the golf club W, the direction of flight of the ball can be controlled. The 45 tapered fingers 2 and 3 will give the golf ball a spin either clockwise or counterclockwise depending upon the particular position of the tee. For example, the position illustrated in FIG. 5 is such that the ball and tee are in placement for a slice, that is a sharp curving of the golf ball to the right (for a right-handed golfer) upon leaving the tee. Similarly, FIGS. 6 and 7 illustrate the positioning for a straight drive and a hook, respectively.

In consequence, this device will enable the ordinary golfer to hook or slice a golf ball whenever he so desires. 55 Since the golfer will know beforehand the usual deficiencies in his swing, that is, whether he has a normal hook or slice, he can compensate for this simply by indexing the tee to afford the desired counterinfluence. If the golfer normally has a hook in his drives, he would position the tee and golf ball as shown in FIG. 5. If his drives normally slice, then the golf ball and tee would be positioned approximately as illustrated in FIG. 7 to compensate for this. If the golfer's drives are normally straight, then, of course, the tee would be positioned as 60 shown in FIG. 6, that is with the club face squarely striking the golf ball midway between the fingers.

The device herein illustrated also enables golfers to obtain greater distance in their drives. Since fingers 2 and 3 are flexible and the ball is gripped therebetween, it 70 will be retained within the tee for a fraction of a moment longer than with the normal tee. This will cause the ball to be resiliently compacted to a greater degree by the

impact of the club and consequently offer less resistance to flight during the first few seconds thereof.

This device will normally be made of rubber or a flexible plastic, such as polyethylene. However, other similar materials can be employed with the only requirement being that fingers 2 and 3 be of a flexible resilient material. To that end, base portion 1 can be of the same material as fingers 2 and 3 or alternatively can be made of metal such as aluminum or of other suitable material.

It is also to be understood that, although in the preferred embodiment the device is of tubular design, the device can be one in which base portion 1 is of any suitable shape with the finger members being generally arcuate in cross-section and positioned generally diametrically opposite each other to support a golf ball therebetween.

It is thus seen that this invention has achieved the stated objects by the provision of a novel golf tee which is relatively simple in construction and which comprises a base portion and a pair of vertically extending flexible fingers thereon, each of the fingers being positioned generally diametrically opposite the other and spaced apart sufficiently to support and grip a golf ball near its midportion when placed in operative position.

Other modes of applying the principle of the invention may be employed, change being made as regards the details described, provided the features stated in any of the following claims, or the equivalent of such, be employed.

I, therefore, particularly point out and distinctly claim as my invention:

1. A golf tee comprising a base portion and a pair of vertically extending flexible fingers on said base portion, said fingers being formed from a resilient flexible material and being generally arcuate in cross-section and positioned generally diametrically opposite one another about the circumference of said base portion, said fingers being spaced apart and being the sole means for supporting a golf ball substantially about its equator.

2. The golf tee of claim 1 in which its lower rear portion is undercut to partially receive the face of a golf club when striking a golf ball positioned on said tee.

3. The golf tee of claim 1 in which the top surfaces of said flexible fingers are sloped forwardly upwardly.

4. The golf tee of claim 1 in which lip members are provided on the inside of said flexible fingers to assist in supporting and positioning a golf ball between said fingers.

5. The golf tee of claim 1 in which said base portion has a front wall extending between said fingers in the region below the lower surface of a golf ball when held between said flexible fingers.

6. The golf tee of claim 1 in which said flexible fingers taper in thickness from front to rear.

7. The golf tee of claim 1 in which said base portion is tubular.

8. The golf tee of claim 1 in which means are provided between said flexible fingers for supporting and vertically positioning the underside of a golf ball.

9. A golf tee comprising a vertically tubular base portion with an undercut in the rear side thereof, a pair of flexible fingers extending vertically upwardly from said base portion, each of said fingers being positioned generally diametrically opposite the other to support a golf ball therebetween, said fingers being spaced apart and being the sole means for gripping a golf ball resiliently near the equator thereof, said flexible fingers tapering in thickness toward the rear of the tee and the tips of said fingers sloping upwardly from the rear to the front thereof, said base portion having a front wall located below the lower surface of a golf ball when positioned between said fingers, and a pair of lip members on the respective inner faces of said fingers to assist in the support and positioning of a golf ball when placed between said fingers.
